UNITED STATES PATENT OFFICE.

CHARLES M. HANNA, OF LOGANSPORT, INDIANA.

VALVE.

1,247,826.

Specification of Letters Patent. Patented Nov. 27, 1917.

Application filed May 29, 1915. Serial No. 31,257.

To all whom it may concern:

Be it known that I, CHARLES M. HANNA, citizen of the United States, residing at Logansport, in the county of Cass and State of Indiana, have invented certain new and useful Improvements in Valves, of which the following is a specification.

My invention relates to valves; has particular reference to an improved combined 10 thermostatic and float valve wherein provision is made for an automatic operation under varying conditions incident to use of the valve in connection with hot water for steam heating plants or systems; and may 15 be said to consist in the novel construction, combination and arrangement of parts hereinafter described and specifically pointed out in the claim.

In the drawings, annexed:

20 Figure 1 is a view, partly in section and partly in elevation, illustrating in detail the construction of my improved valve;

Fig. 2 is a detail section of one of the valve parts; and

25 Fig. 3 is a similar view on line 3—3 of Fig. 2.

Like numerals of reference designate like or corresponding parts throughout the several views.

30 Referring now to the drawings by numerals, 1 designates an open top chamber within which the valve mechanism comprising the present invention is arranged.

The steam and water supply necessary to 35 operation of the mentioned valve is conveyed to the chamber 1 via an induction pipe extension 2, open to the radiator (not shown) in connection with which the valve may be used. The extension 2 is preferably 40 exteriorly threaded as indicated at 3 and equipped with a polygonal or wrench-engaging portion 4, said wrench-engaging portion facilitating attachment and detachment of the valve structure when used as 45 hereinbefore pointed out. A cover 5 is made detachable relatively to the chamber 1, which cover, as shown to advantage in Fig. 1, is equipped with a depending integral valve casing structure 6 and a like upwardly 50 extending casing structure 7, the former structure 6 being enlarged at its free end or as indicated at 8, the enlargement terminating in a valve seat 9. A second valve seat 10 is formed upon the free or upper 55 end of the casing structure 7, with which seat a valve 11 is engageable, a spring 12

being arranged above the valve to normally maintain said valve in engagement with its seat. The extension or valve casing structure 7 is exteriorly threaded as indicated 60 at 13 to receive an interiorly threaded valve cap 14, against the inner top wall of which the spring 12 abuts, the opposite end of mentioned spring, as implied from the description above, being in engagement 65 with the valve 11. Apertures 15 are formed in the cap 14 for a purpose to be herein-after disclosed.

A valve stem 16 is made integral with the valve 11 and of a size to frictionally 70 contact with and snugly engage the inner wall of the valve casing structure 6, the stem, by reason of the mentioned engagement affording a guide whereby movement of the valve 11 against tension of its associate spring 12 may be directed. 75

A second valve 17 is mounted for movement at the lower end of the structure 6 and into and out of engagement with the valve seat 9. A stem 18 is made integral with the 80 last mentioned valve, which stem, like the stem 16 noted above, is adapted for frictional engagement with the inner wall of the structure 6. Channels or longitudinally extending passage ways 19 are formed in the 85 valve stem 18, which channels, with like channels or passage ways 20, afford a means of escape for steam under certain conditions incident to use.

Affixed as at 21 to the valve 17 is a float 90 22, the mentioned float, when the chamber 1 is partially filled with water, rising (because of its inherent buoyancy), and by reason of its engagement with the valve 17, causing said valve to automatically close, to in this 95 manner close communication between the interior of the chamber and the outlet via the opening 15 noted above. Normally float 22 is supported in a position whereby to space the valve 17 from its seat by means of superposed communicating thermostatic chambers 23, the lowermost of which is affixed at one end as at 24 to an arcuate supporting plate 25 in turn affixed to or made integral with the chamber. If desired, the chamber 23 100 may be filled with a substance, expansible under high temperature, to, by such expansion, cause the float 22 to be raised and the valve 17 thus closed. 105

In operation, and in the event that steam 110 enters the chamber 1 it is evident that valve 17 will automatically close, the expansion of

the thermostatic chambers 23 causing the mentioned valve to be raised until firmly in contact or in engagement with its seat. Should condense steam or water accumulate 5 within or enter the chamber 1, it is evident that the float 22 will rise therewith to in this manner automatically close the mentioned valve. Normally, as indicated in Fig. 1, said valve 17 is opened, the weight of the 10 float 22 acting as a retracting means whereby said valve is thus maintained. Should the automatic valve operating means fail to close the mentioned valve, it is evident that the steam or water pressure, if excessive, will 15 automatically unseat the valve 11 and, through opening 15, permit such excess steam or water to escape. Movement of the valve 11 is against tension of the spring 12.

In reduction to practice, I have found that 20 the form of my invention, illustrated in the drawings and referred to in the above description, as the preferred embodiment, is the most efficient and practical; yet realizing that the conditions concurrent with the 25 adoption of my device will necessarily vary, I desire to emphasize the fact that various minor changes in details of construction, proportion and arrangement of parts may be resorted to, when required, without sacrificing 30 any of the advantages of my invention, as defined in the appended claim.

Having thus fully described my invention, what I claim as new and desire to secure by Letters Patent, is:—

A radiator valve comprising a casing having 35 an inlet opening at one end, a tubular valve casing formed at its other end, said tubular casing having each end enlarged to form annular recesses, a pair of valve structures, each comprising a cylindrical body 40 fitting said tubular casing for sliding movement, a frusto-conical valve formed on the remote ends of said cylindrical body for engagement with the valve seat formed on the ends of the tubular valve casing, each of 45 said valve structures being perforated with passages which open at one end on the outer faces of the valve and at their opposite ends on the side of the cylindrical body, and into the annular recesses, a spring for retaining the outer valve upon its seat, a float connected to the inner valve structure, and a thermostatic element contacting with said 50 float whereby to move said inner valve structure to closed position when said thermostatic element is expanded.

In testimony whereof I affix my signature in presence of two witnesses.

CHARLES M. HANNA.
